CAR DOOR.

APPLICATION FILED FEB. 25, 1905.

2 SHEETS—SHEET 2.

UNITED STATES PATENT OFFICE.

HARRY L. ROGERS, OF ALTOONA, PENNSYLVANIA.

CAR-DOOR.

No. 839,648.

Specification of Letters Patent.

Patented Dec. 25, 1906.

Application filed February 25, 1905. Serial No. 247,387.

To all whom it may concern:

Be it known that I, HARRY L. ROGERS, a citizen of the United States of America, residing at Altoona, in the county of Blair and State of Pennsylvania, have invented new and useful Improvements in Car-Doors, of which the following is a specification.

The invention relates generally to improvements in doors for freight or other cars, and more particularly to means for supporting or mounting the door with relation to the car to permit its convenient closing and opening.

The main object of the invention is to provide suitable hanging mechanism for the door arranged to be operated to move the door flush with the car side in closing the same and to shift the door bodily into a plane beyond the car side to permit the opening operation of the door.

Another object of the invention is to provide means whereby the door may be readily locked in opened position, which means is also adapted to frictionally lock the door at any position intermediate the fully-closed and fully-opened positions.

Another object of the invention is to provide a construction by which the door when fully closed is securely locked at its top, bottom, and intermediate point.

Another object of the invention is to construct and arrange all mechanism so that the operating-levers thereof move in a plane parallel to the side of the car, whereby unnecessary projecting parts are avoided and the minimum of space required for the manipulation of the mechanism.

With these objects in view the invention, broadly stated, consists in a door supported at its upper end in a pivotally-mounted track, which track is adapted to be turned from a normal position to bodily project the door into a plane flush with the car side or into a plane parallel with but beyond the car side, brackets arranged adjacent the bottom of the car-door and adapted to lock the same in closed position or in opened position, and means intermediate the track and brackets to lock the door in closed position.

The preferred details of construction of my invention will be fully described in the accompanying specification, reference being had to the drawings herewith, in two sheets, in which—

Figure 1 is a view in elevation, showing a portion of a car, the door thereof being provided with my improved operating mechan-

ism, the door being shown in closed position. Fig. 2 is a similar view, the door being shown locked in opened position. Fig. 3 is an end elevation of the car side, showing the door and operating parts. Fig. 4 is an enlarged vertical longitudinal section illustrating the track and door-hanger. Fig. 5 is a transverse section of the same. Fig. 6 is a transverse longitudinal section through the door and a portion of the car, illustrating the intermediate locking mechanism for the door. Fig. 7 is a broken sectional view illustrating a feature of the door construction. Fig. 8 is a perspective view of the supporting and locking bracket. Fig. 9 is a broken perspective of the lower portion of the door, showing particularly the stiffening-brace and the channel formed between said brace and the door for the discharge of water flowing down the surface of the door.

Referring particularly to the drawings, 1 represents the car body or side, and 2 the door, arranged to fit flush within the casing 3.

It is highly desirable in the car-door construction that the door shall when closed rest within the casing flush with the car side in order to avoid undesirable projections beyond the car-body and also that in opening the door the same shall be moved lengthwise of the car in a plane beyond the side thereof.

I have provided particular mechanism for accomplishing this result, in which 4 represents a track arranged lengthwise of the car and slightly above the upper end of the door 90 2. The track comprises a hollow box-like member having a narrow aperture 5 in its lower wall which communicates with the interior section of the track. The aperture 5 is of less width than the interior of the track 95 member to provide shoulders or ways 7 adjacent said aperture 5, designed to receive and support the door-hanger. At the rear end—that is, the end remote from the door-opening—the track is pivotally supported in a 100 bracket 8, secured to the side of the car through the medium of a stud 9, projecting from the track and entering an opening or bearing 10 in the angle-web 11 of the bracket. The connection between the stud 9 and bearing 10 is a comparatively loose one to permit the hereinafter-described movement of the track. The forward end of the track is also provided with a longitudinally-projecting stud 12, which enters an opening formed in 110 a link 13, pivotally mounted at 14 on the side of the car. An arm 15, loosely connect-

ed with the stud 12 beyond the link 13, depends from said stud and is connected at its lower end to a rod 16, adapted for vertical sliding movement with relation to the car 5 through the medium of a hand-lever 17, pivoted to the car side at 18 and connected to said rod 16. The lever, as will be evident from the drawings, is adapted for movement in a plane parallel to the side of the car and 10 is arranged to be held or locked in operative position by a spring-catch 19, a stop 20, arranged adjacent the catch, serving to limit the throw of the lever in this direction. By 15 preference the stop 20 is of the usual staple form, whereby the ordinary lock and seal, connected with the stop and encircling the arm of the lever, may be used when desired.

The door is supported by hangers 4', comprising hinged members, one of which is secured to the door, the other projecting through the aperture 5 in the track member and carrying at its free end guide-rollers 5', arranged to rest upon and travel lengthwise the ways 7 of the track member.

25 For supporting and locking the lower end of the door when in closed position I provide brackets 21, secured to the car side immediately contiguous the lower corners of the door. These brackets are of peculiar construction and adapted to secure the lower 30 end of the door in closed position and at the same time afford an effective brace and support for the door-posts. Each of the brackets includes a base-plate 22, which projects at 35 right angles from the face of the car side, and a vertical wall 23, projecting above and below the base at the inner edge thereof. That portion of the vertical wall lying below the base is designed to be bolted to and snugly 40 against the longitudinal sill of the car, while that portion of the vertical wall projecting above the base is securely bolted directly to the door-posts, it being understood that the siding covering the side frame of the car 45 is cut away to permit this arrangement of the brackets. The base-plates 22 are each provided at the central portion of their outer edges with a vertical web 24, and immediately in rear of this web and on the upper surface 50 of the base-plate are arranged transverse or rearwardly-extending ribs 25, which ribs project rearwardly beyond the base-plate and are adapted to overlie and rest directly upon the car-sills, the flooring of the car or that 55 portion thereof immediately beneath the door being cut away to permit of the rearward projection of the ribs. The blocks 25 are reduced at their rear ends to provide shoulders or stops 26, which shoulders are in 60 alinement with the outer surface of the car side and serve as stops or locks behind which the lower edge of the door is held when in closed position.

The third bracket 27 is secured to the car 65 side in horizontal alinement with the brack-

ets 21, this latter bracket being positioned at the limit of travel of the door when opened and being formed with a right-angle vertically-projecting web 27', within which the corner of the door is received to limit its movement. 70

To lock the door intermediate its upper and lower edges, I provide a T-lever 28, pivotally connected about centrally of the door, and to the free end of each short arm 29 of this lever I connect a sliding bar 30. The 75 free ends of the bars 30 are formed with latches 31, preferably integral with the bar and offset therefrom, as shown, said latches working in a recess 32, formed in the edge of the door and covered by an ordinary metal 80 housing 33. Keepers 34 are formed in the edges of the door-posts, being arranged to conveniently receive the latches 31. The lever 28, as will be evident from the drawings, operates in a plane parallel to the face of 85 the door and is designed to be held in inoperative position by a catch 35, and locked in operative position through the medium of the usual sealing staples 36, and a longitudinal slot 37 in said lever, designed to engage 90 one of said staples in the usual manner.

38 represents a stiffening-brace for the lower edge of the door comprising a strip of metal extending on both front and rear of the door and beneath the lower edge thereof, 95 which strip may be the usual angle-iron or of such other structure as may be found desirable. The strip extends upward on the face of the door sufficiently far to prevent rubbing contact of the door and brackets in the necessary operation of the parts and is further designed to serve as an outlet and conveyer for any water which may run down the surface of the door and which would otherwise tend to speedily destroy the lower edge of the door 100 proper. To accomplish this object, a narrow channel 39 extends longitudinally between the brace 38 and the extreme lower edge of the door proper, this channel being open at its end and intermediate the end in communication with small openings 40, formed in the brace-strip. By this means any water finding its way down the face of the door will enter the channel 39 and escape through the 105 openings 40 or through the end of the channel and out through vertical openings 41, formed in the brackets 21 and arranged to directly underly the ends of said channel when the door is in closed position. The bracket 27 is also formed with a vertical opening 42, which, together with a second opening 43, formed in the intermediate bracket 21, registers with the open ends of the channel to permit escape of the water when the door is in 110 opened position.

Assuming the parts constructed and arranged as described and the door in closed position, the operation is as follows: On reference to Fig. 3, in conjunction with Fig. 1, which illustrate the door in closed position, 115

it will be seen that the lever 17 is within the catch 19 and against the stop 20, and that the track is rocked from its normal position to move the hanger, and thereby the door inward—that is, within the casing flush with the side of the car. The lower end of the door, it will be noted, rests in rear of and against the stops 26 of the brackets 21, the lever 28 being also in vertical position, which projects the bars 30 outward, forcing the latches 31 into their keepers 34. In this position of parts the door is closed and is locked at top, bottom, and intermediate point. When desiring to open the door, the lever 28 is moved from its vertical position to and in engagement with the catch 35, in which position the latches 31 are withdrawn from the keepers 34 and the intermediate lock is released. The lever 17 is now released from the catch 19 and swung downward until its free end is practically in contact with the web 24 of the contiguous bracket 21. By this movement the rod 16 is elevated, moving upward the arm 15, and thereby the track 4; but as the latter is pivotally mounted at each end its upward movement tends to practically rock the track on its main axis, the door being hung from the track in a plane between the pivot of the track to link 13 and the inner pivot of said link 13, thus causing the track to rock and carry the door out of the doorway, and thereby cause the track to assume a normal position, which is, with the aperture 5, at the lowest part of the track and the lower wall of the track member practically at right angles to the face of the car side. This operation of the track, it will be noted, raises the door, through the connection of the track with the pivoted link 13, and this elevation of the door withdraws its lower edge from behind the stops 26. In conjunction with the elevation of the door the turning of the track on its axis moves the upper end of the door outward from the door-casing, and as the lower end of the door has been withdrawn from the rear of the stops 26 the entire door will by gravity swing into a vertical position which is in a plane parallel to but slightly beyond the side of the car. The door may now be moved rearward on the track 4 through the medium of the hangers, such movement being continued, if desired, until the door contacts with the rear bracket 27, it being noted that the movement of the door longitudinally of the track is materially assisted by the elevation of one end of the track. In this position the door is fully opened, and if it is desired to lock the door in this position the lever 17 is again moved to operative position to turn the track, which operates to slightly lower the door and bind the same against the side of the car. In lowering, the forward edge of the door drops below the side edge of the rib 25 on the intermediate bracket 21, and the door is thus securely

held against any longitudinal movement whatever. A reversal of this operation will serve to again seat the door in its casing, as will be understood.

It will be noted that when adapted for longitudinal movement the lower edge of the door moves slightly above the rib 25 of the intermediate bracket 21, and by this construction I am enabled to frictionally secure the door at any point desired intermediate 75 its fully opened and closed positions, as it is only necessary when the door has reached the desired position to operate the lever 17 to tilt the track into inoperative position when the door will drop into frictional contact with the rib 25 of the bracket 21 and be held against longitudinal movement.

It will be noted that the door is provided with the usual operating-handle 44 and that the side of the car has the usual limiting-stop 85 45 for the central portion of the door. To protect the track against the elements, I prefer to partially cover the same with a hood 46, connected to and supported from the facing of the car, with its free end overlying and 90 extending below the track, as shown in Fig. 3.

Having thus described the invention, what is claimed as new is—

1. In combination with a structure having a door-opening, of a door therefor, means for movably supporting the door and connections intermediate said means and the structure, whereby said means may be moved from the door-opening and elevated at one end. 100
2. The combination with a structure having a door-opening and a door therefor, of a track for movably supporting the door, and means for moving the track in a direction away from the door-opening and elevating one end thereof. 105
3. The combination with a structure having a door-opening and a door therefor, of a track movably supporting the door, and means for tilting the track from the door-opening and elevating one end thereof. 110
4. The combination with a structure having a door-opening and a door therefor, of a track pivotally supported by the structure, and means for rocking said track in a direction away from the door-opening and elevating one end thereof. 115
5. The combination with a structure having a door-opening and a door therefor, of a track pivotally supported by the structure, 120 and means connected with the track and adapted by a single operation to move the track away from the door-opening and elevate one end thereof.
6. The combination with a structure having a door-opening and a door therefor, of a track pivotally supported at one end by the structure, and means intermediate the opposite end of the track and the structure and adapted for operation to move said end in a 125 130

direction from the door-opening and elevate it in a plane above the opposite end.

7. The combination with a structure having a door-opening and a door therefor, of holding means for securing the lower end of the door in the door-opening, a track movably supporting the upper end of the door, and a connection between one end of the track and the structure adapted on operation to move the track in a direction away from the door-opening and free the lower end of the door of the holding means, said connection simultaneously elevating one end of the track.

15 8. The combination with a structure having a door-opening and a door therefor, of a track pivotally mounted at one end in a fixture projecting from the structure, a movable member pivotally supporting the oppo-

site end of the track, means connected with 20 the door and movable along the track, and means for rocking the track on its pivotal connections in a direction away from the door-opening and elevating said member, whereby the end of the track supported by 25 the member is moved to a plane higher than its opposite end.

9. A car-door having a stiffening-brace at its lower end, a channel formed in said brace intermediate the lower edge of the car-door 30 and the brace, and openings formed in the brace to communicate with said channel.

In testimony whereof I affix my signature in presence of two witnesses.

HARRY L. ROGERS.
